UNITED STATES PATENT OFFICE

2,081,276

LOCOMOTIVE STOKER

Charles P. Hubler, East Stroudsburg, Pa., assignor, by mesne assignments, to The Standard Stoker Company, Inc., a corporation of Delaware

Application April 5, 1928, Serial No. 267,543
Renewed September 5, 1935

5 Claims. (Cl. 110—101)

This invention relates to improvements in methods and means for stoking fires, and more especially to an improved form of stoker for railroad locomotives.

5 An object of the invention is to provide a stoker with an automatic means for conveying fuel through a firing opening.

Another object is to provide a swinging fuel elevator that can be swung into and out of position.

10 A further object is to provide means for forcing the fuel across the blower jet onto a scattering platform, this being accomplished with but a single elevator.

15 Still another object is to minimize the weight on the locomotive wheels by mounting the stoker engine on the tender and then transmitting the power across to the elevator on the locomotive.

Another object of my invention resides in an 20 improvement in stokers having offset conveyers, which improvement consists in providing a gear train at the rear of the tender conveyer operatively connected therewith, supplying motive power to such gear train and providing a power 25 take-off shaft from such gear train, said shaft extending along the tender conveyer and at its forward end being operatively connected to the lower rearward end of a conveyer delivering to the locomotive firebox, which conveyer is offset 30 from the tender conveyer.

Yet another object is to provide a method and means of fuel distribution which includes the use of a centrally-located fuel conveyer, forcing the fuel directly against a single, central elevator, the fuel being thereafter forced over a blower jet.

35 All these and other objects, as suggested below, are attained with the method and means hereinbelow described, and illustrated in the accompanying drawings, in which—

40 Figure 1 is a longitudinal vertical section showing the essential mechanism of the stoker in its relation to the tender and the locomotive cab; Fig. 2, a transverse sectional view taken on line 2—2 of Fig. 1; Fig. 3, a top plan view, with parts shown in section, of the assembled device, taken through the plane 3—3 of Fig. 1; and Fig. 4, a combined sectional and elevational view through plane 4—4 of Fig. 3.

Like numerals refer to like parts throughout 50 the several views.

The stoker mechanism is positioned partly in the locomotive cab 10, and partly in the tender 11. It consists essentially of a vertically-swinging elevator comprising a casing 12, surrounding 55 a revolvable screw conveying-member 13, mount-

ed in bearings in casing 12, and substantially along its longitudinal axis.

There is a flat surface on the outside of casing 12 at 14, Fig. 1, and in contact with this surface is a threaded adjusting member 15, mounted in the fire box wall 16, this member 15 being adapted to be turned to move the entire conveyer-casing 12, with its attendant parts, toward and away from the furnace or fire-box wall, thus enabling a close fit to be maintained at 17 where the top 10 of the conveyer slides over the fire-door plate 18.

This arrangement not only permits the maintenance of a close fit along joint 17, Fig. 1, but allows the whole elevator casing 12, to be slid back in case of any substantial expansion of the 15 boiler of the locomotive, which would otherwise prevent the free swinging of the elevator.

The fuel is carried from the tender 11, and forced directly against the single central swinging elevator 13, in its casing 12, by means of a centrally-located conveyer screw 19, supported in its casing 20, near the locomotive end, by a bearing 21, and at its opposite end by a sliding clutch connection to its drive shaft 22.

Drive shaft 22 is rotated by a gear 23 keyed 25 to it, and in turn driven by a pinion 24, driven from the stoker engine 25 through a drive shaft 26, Fig. 3, with its universal joints 27.

Immediately below gear 23, Fig. 1, and in mesh with it, is a second driven gear 28 keyed 30 to a drive shaft 29 which in turn drives, through a universal joint 30, a drive shaft 31, and a pair of bevel gears 32 or other suitable means, the vertical fuel conveyer 13. The gear ratios in this complete driving system are such as to feed 35 the fuel along conveyer 19 and up the conveyer elevator 13 at the proper speed.

The elevator casing 12 and screw 13 swing in a suitable bearing about an axis coincident with the axis of drive shaft 31, Figs. 1 and 4.

40 The coal hopper 33 in tender 11 has an opening 34, Figs. 1 and 2, in its floor, immediately beneath which the opening in the horizontal conveyor casing 20, Fig. 2, is flared out, as shown, to receive the fuel which drops in by gravity.

45 The arrangement of the swinging elevator 13 is shown clearly in Fig. 4. As previously explained, it pivots about bearings along the axis of shaft 31. The operator stands on the floor of the cab. He opens a valve by pressing its spring-held stem 35 to admit steam or other power medium to one end of a cylinder 36 to force its piston 37 to the left, as shown in Fig. 4, and so by means of a connecting rod 38 to swing the conveyer casing 12 with its conveyer to the left 50 55

into the position shown in Fig. 4, thus exposing the fire door hole 39. This swinging movement is against the tension of a spring 41 arranged as shown which normally retains the elevator 12 5 in front of the fire door opening 39.

A small fire door 40 is used for raking the fire under the boilers and for a small amount of firing, to "trim" the fire. The spring 41 also keeps the door closed when the cylinder 36 is without 10 steam, air, or other motive power.

From the arrangement thus described it is apparent that the conveying elevator can be swung off to one side to expose the fire-door hole, and also by means of the power cylinder 36 it can 15 be swung back and forth, thus acting as an automatic fire door, opening and closing between each scoop of coal or between each series of scoops.

It will be noted that swinging the elevator 13 does not affect the transmission of power to it 20 through the bevel gears 32, since the axis of shaft 31 coincides with that on which the elevator is swung. It will also be noted that the large flange 42, Fig. 4, prevents spilling of the coal when the elevator is swung over. The elevator screw 13 25 revolves slightly during the swinging operation. The purpose of this device is, briefly, to convey and raise fuel to the firing opening of a boiler, and feed the fuel to the fire in proper amounts, the operations being suitably timed for continuous 30 performance, and being entirely automatic.

One of the most novel features of this construction is the relative location of the blower jets 43, Figs. 1 and 3, and the scattering platform 44 and elevator screw 13. Conveyor 13 forces the coal 35 across the jets 43 and onto platform 44 as shown. This is the first time this has been accomplished in a stoker with a single elevator. Another point of novelty here is the location of the blower jet between the scattering platform and the elevator screw. It will be noted also that the design and 40 arrangement of the fuel elevator 13 is small and low enough to force the coal into the ordinary fire hole without running it too high up in front of the hole.

From the foregoing, it will be seen that I have 45 provided for a source of power located in the tender and carried forward to the locomotive to operate the elevating screw and that I force the coal directly into the elevating screw, there being 50 no obstructions beyond the end of the conveying screw.

I have also provided a single elevating screw 55 lying close to the surface of the boiler and having a top fashioned to enable wet coal, which offers more resistance than dry coal, to be readily discharged onto the scattering platform.

It will be noted I have also fashioned the end 60 of the elevating screw to a form which will be efficient in discharging the coal and will not crush or pulverize it.

All the features above go to make a small compact stoker which will feed the fire through a fire hole that in size is safe to withstand explosions and is of a convenient height above the 65 deck.

It is to be understood that the present disclosure is for the purpose of illustration only, and that the invention is not limited thereto. To those skilled in the art, many modifications of 70 the invention will be readily apparent, and it will also be obvious to such skilled persons that part of the device may be used without other parts thereof, and steps in the method without other steps thereof, many such combinations of

the parts readily suggesting themselves. Therefore, it should be, and is to be distinctly understood that for a definition of the limitations of the invention, reference must be had to the appended claims.

Having now described the invention, what is claimed as new and for which Letters Patent of the United States is desired, is:

1. The combination with a locomotive having a backhead provided with a firing opening therein, of a tender for said locomotive, a conduit disposed beneath the deck of the tender, an elevator conduit on the locomotive in communication at its lower end with said first named conduit and at its upper end with said opening, said elevator conduit being arranged to swing laterally about its lower end for moving the upper end thereof from in front of said opening to one side thereof, power means for swinging said elevator conduit and foot actuated means for controlling said power means.

2. In a locomotive having a backhead provided with a firing opening therein, a tender for said locomotive, a conveyor conduit mounted in the tender, an upright conduit on the locomotive in communication at its lower end with the first named conduit and at its upper end with said opening, said upright conduit arranged to be swung laterally into and out of register with said opening about a pivot at its lower end, means for 30 swinging the upright conduit, and elevating means within the upright conduit.

3. In a locomotive having a backhead provided with a firing opening therein, a tender for said locomotive; a conveyor conduit mounted in the 35 tender, an elevator conduit on the locomotive in communication at its lower end with the first named conduit and at its upper end with said firing opening, said elevator conduit arranged to be swung laterally about its lower end into and out 40 of register with said firing opening, means for sealing the portion of the forward end of said conveyor conduit that is out of register with the communicating end of said elevator conduit as the latter swings laterally.

4. The combination with a locomotive having a backhead provided with a firing opening therein, a tender for said locomotive, a conveyor conduit mounted in the tender, an upright conduit on the locomotive in communication at its lower 50 end with the first named conduit and at its upper end with said opening, said upright conduit being substantially parallel with said backhead and arranged to swing about its lower end in a plane parallel to said backhead for moving the upper 55 end thereof from in front of said opening to one side thereof and means for swinging said upright conduit.

5. The combination with a locomotive having a deck and a firebox provided with a backhead 60 having a firing opening therein, a tender for said locomotive, a conveyor conduit mounted in the tender and extending forwardly therefrom beneath said locomotive deck, a stoker conduit on the locomotive in communication at its lower end with the forward end of said conveyor conduit and extending upwardly through said deck and communicating at its upper end with said firing opening, said stoker conduit being arranged to swing laterally about its lower end for moving the upper end thereof from in front of said firing opening to one side thereof and means for swinging said stoker conduit.

CHARLES P. HUBLER.
